Attorney, Agent, or Firm—William B. Ritchie

[**] **Term:** **14 Years**

[57] **CLAIM**

[21] **Appl. No.:** **71,146**

The ornamental design for ornamental sink spray sponge attachment, as shown and described.

[22] **Filed:** **May 22, 1997**

DESCRIPTION

[51] **LOC (6) Cl.** **08-05**

FIG. 1 is a front, perspective view of the ornamental sink spray sponge attachment showing my new design; and, FIG. 2 is an end view of the invention; all the other end views being identical.

[52] **U.S. Cl.** **D32/43; D32/40; 401/289**

The shading on the body of the sponge is fragmentarily shown for ease of illustration.

[58] **Field of Search** **15/244.1, 244.4,**

The line pattern shown on the body of the sponge represent color; specifically the color yellow, a characteristic feature of the claimed design.
